UNITED STATES PATENT OFFICE

JOHN BRICKEN, OF LOS ANGELES, CALIFORNIA, ASSIGNOR OF ONE-HALF TO REGAN FORGE & ENGINEERING COMPANY, OF SAN PEDRO, CALIFORNIA, A CORPORATION OF CALIFORNIA, AND ONE-HALF TO E. F. BRITTEN, JR., OF MAPLEWOOD, NEW JERSEY.

WELL DRILLING AND PUMPING APPARATUS

Application filed July 30, 1926. Serial No. 126,002.

My invention relates to improvements in oil well drilling and pumping apparatus.

The principal object of the invention is to provide improved apparatus which is arranged to adjust itself automatically for operating at maximum capacity without overloading. The well drilling feature of the invention is broadly characterized by the provision of means whereby when the drill encounters material offering unusual resistance, the feed of the drill is automatically lessened or retarded, while the feed is increased to maximum drilling capacity when the nature of the material warrants the same.

A further object of the invention relates to the provision of means whereby a gage or indicator is provided for indicating the resistance offered by the material in which the drill may be working, whereby proper functioning of the automatic devices can be observed, to prevent overloading or underloading, thus guarding against damage to the equipment or poor economy in operation, respectively.

Another object is to provide an apparatus which when installed for drilling a well may with few changes be left in position for carrying on the pumping operation.

A still further object relates to the provision of pumping mechanism adapted to operate a long stroke pump with minimum power consumption.

Further objects relate to various features of construction and arrangement of parts which will become apparent from a consideration of the following specification and accompanying drawings, wherein

Figure 1 is a broken front elevation of the improved apparatus.

Fig. 2 is an enlarged broken front elevation of the apparatus, parts of the same being shown in section.

Fig. 3 is a broken plan view of the parts shown in Fig. 2.

Fig. 4 is a vertical sectional view taken on line 4—4, Fig. 2.

Fig. 5 is an enlarged vertical sectional view showing the portions of the brake bands and operating mechanism.

Fig. 6 is a vertical section taken on line 6—6, Fig. 2.

Fig. 7 is an end elevation, partly in section, and parts of the spring housing being broken away for the purpose of clearness.

Fig. 8 is an enlarged horizontal sectional view taken on line 8—8, Fig. 7.

Fig. 9 is a vertical section taken on line 9—9, Fig. 2.

Fig. 10 is a broken side elevation illustrating the apparatus as arranged for operating an oil pump.

Fig. 11 is a vertical sectional view of the chain, hoist pulley, and associated mechanism.

Fig. 12 is a transverse sectional view of the pulley, taken on line 12—12, Fig. 11.

Fig. 13 is a vertical section taken on line 13—13, Fig. 11.

Fig. 14 is a vertical sectional view taken on line 14—14, Fig. 2.

In the drawings, I have shown a number of I-beams 10 for supporting the apparatus, but it will be understood that other supports may be provided when desirable. Carried by the beams 10 is a motor, indicated generally by numeral 11, which is adapted to drive a horizontal shaft 12 which is journaled in bearings 13 and 14, as shown in Figs. 1 and 2.

The frame or casing 15 of the motor is not rigidly fixed, but is adapted to oscillate in a direction opposite the direction of rotation of the shaft 12 due to the counter-force exerted by the rotor of the motor upon the field coils (not shown) on the interior of the casing 15. A channel member 16 is anchored to the beams 10 by the bracket 17, or like. Within the channel of member 16 is a coil spring 18 between the ends of which is a lug

19 which extends outwardly from the casing 15. The spring 18 is prevented from sliding circumferentially in the channel by lugs 16, (see Fig. 8) and exerts pressure on the lug 19 and tends to hold the motor casing in the center position shown, for instance, in Figs. 2, 7 and 8.

When the motor is started, the counter-force exerted by the load will tend to move 10 the casing 15 in a direction opposite the direction of rotation of the shaft 12 which tendency to rotate will be resisted, more or less, by the spring 18. If the resistance to the rotation of the motor is great, the counter- 15 force will be likewise great, and the casing 15 will oscillate through a greater arc. By providing a dial 20 which may be secured, for instance, to the channel member 16, as shown in Fig. 2, in front of which to the 20 casing 15 is secured a pointer 21, it is possible to observe the degree of movement of the casing 15 when the motor is running, which movement will correspond to the torque of the shaft 12, and will, in effect, indicate the 25 load on the motor or the resistance being offered to the rotation of a drill or pump being operated by suitable connections with the shaft 12.

A tower 22 is provided on the top of which 30 is mounted a chain operating mechanism, or hoisting pulley, indicated generally by numeral 23. The mechanism comprises a bevel gear 24 which meshes with a pinion 25 secured to the end of the shaft 27, the upper 35 end of which is secured in a bearing 28. The lower end of shaft 27 has secured thereto a disk clutch, indicated generally by numeral 30. The clutch 30 is of standard construction and need not be specifically described. 40 The shaft 27 may be tubular and from the lower end thereof the pin 31 extends into a corresponding bore formed in the shaft 32 having a pinion 33 at its lower end. A stationary sleeve 34 is supported by bracket 45 34 which may be secured to the base members 10, which sleeve carries the disks 35. The sleeve 34 is threaded, as at 36, as shown in Figs. 2 and 4. A driving pinion 37 is secured to the motor casing and rotates therewith, which pinion meshes with the segmental gear 38 carried by the arms 39 which extend from gear 38 to the ring member 40 having interior threads which coat with the threaded portion 36 of the sleeve 34. A 50 pinion 41 is secured to rotate with the shaft 12, as shown in Fig. 2, and upon rotation of said shaft drives the planetary gears 42 (see Fig. 9). The planetary gears 42 are journaled on extensions or stub shafts 43 carried by the web of the drum 44, secured to, and concentrically mounted with which, is a driving pinion 45.

The pinion 45 meshes with the bevel gear 33, previously described. The gears 42 mesh 55 with the internal ring gear 46 on the interior

of the drum 47 which has a bored extension 48 supported by a journal 14, said drum and extension being slidably mounted on the shaft 12. The free end of the extension 48 is provided with a clutch section 49 which is adapted by means of a lever 50 to be moved into and out of engagement with the complementary section 51 secured to the shaft 52 which is journaled in bearing 53. The opposite end of shaft 52, as shown in Fig. 1, 70 is provided with a bevel driving pinion 54 which meshes with the bevel table gear 55 having a sliding and driving fit with the vertical drill shaft 56.

If the apparatus is in operation, and the 80 drill, not shown, encounters material which offers unusual resistance, the counterforce exerted on shaft 12 will cause the casing 15 of the motor to move in a direction opposite to that of the rotation of the shaft. As will be 85 understood, the shaft 52 is driven through the clutch sections 49 and 51 from the extension 48 of the drum 47, which in turn is driven by pinion 41 secured to shaft 12 by means of the gears 42 and internal ring gear 90 46. When the unusual resistance or over-loading just referred to is encountered, the pinion 41 causes the gears 42 to travel circumferentially along the ring gear 46, thereby causing the drum 44 to rotate to which, as 95 was previously explained, is secured the bevel pinion 45. Rotation of the pinion 45 drives the gear 33, which through the intermediary of the clutch 30 rotates shaft 27 in a direction to cause the hoisting pulley 23 100 to lift the chain 57 and the drill shaft 56, thereby lifting the drill to release the over-loading on the apparatus.

Should the drill reach material which offers little resistance thereto, the casing 15 of 105 the motor will move in the direction opposite that just described. The said movement of the casing 15 will rotate the gear 37 and segmental gear 38 causing the ring member 40 to turn on the threads 36 and thereby release 110 the clutch 30 by overcoming the tension of springs 58, whereupon the drill will drop deeper into the well by its own weight, the weight of the drill and other suspended portions, such as the shaft 56 and chain 57, being sufficient to cause this movement. It will 115 therefore be seen that the drilling apparatus described functions automatically to increase or decrease the feeding of the drill in proportion to the load thrown upon the drill by 120 the condition of the rock or material in which the drill is working.

As will be seen in Fig. 2, for instance, the drum 44 is provided with a brake band 59, while drum 47 is provided with the brake 125 band 60. Before the drum 44 can rotate to lift the drill, as described above, the band 59, which normally prevents rotation of said drum, must be released. As shown in Figs. 3 and 5, the ends of said band 59 have links 130

61, 61', secured thereto. The intermediate ends of the links 61, 61' are pivoted to arms 62 and 62', said arms being secured to shafts 63 and 64, respectively. As shown in Fig. 3, 5 the shafts 63, 64, are journaled in suitable bearings to the transverse members of the supporting structure.

Pinion 37, which, as above explained is secured to and rotates with the casing 15 of 10 the motor, meshes with the segmental gear 65 which is mounted and is freely rotatable on shaft 63. An arcuate slot 66 is provided in the gear member 65 into which projects the stud 67 carried by arm 68, which is fixed 15 to the shaft 63. The shafts 63 and 64 are provided with meshing sector shaped gears 69 and 70, respectively, by means of which the rotation of one shaft is transmitted to the other.

20 When the load upon the motor becomes so great that the motor casing 15 rotates, as above described, the pinion 37 will be moved counter-clockwise, as viewed in Fig. 5. Rotation of the pinion 37 causes the segmental gear 65 to move downwardly, as viewed in Fig. 5, and if the movement be sufficient, the upper end of slot 66 will engage the stud 67 causing the arm 68 to move in a clockwise direction and swing the arms 62, 62' 25 in opposite directions to release the band 59 on the drum 44. The slot 66 is long enough to permit of suitable fluctuation of the motor casing before the elevating mechanism is thrown into operation. It is only 30 when the load on the motor reaches a point which has been determined previously to be dangerous that the above automatic operation is effected. A pair of set screws 65' 35 may be provided for varying the effective length of the slot 66, whereby the apparatus can be set to release the band 59 at any predetermined load value. As will be understood, the ratio of the gears is such that upon the releasing of band 59, the power of 40 the motor will be transmitted to pinion 33 for driving the shaft 27 and to thereby lift 45 the drill, as above described, to prevent overloading of the same.

The band 60, previously referred to, is 50 normally loose on the drum 47 when the drilling operating is proceeding. The ends of the band 60 are provided with links 71 and 72, as shown in Fig. 3, the opposite ends of which links are connected to the arms 73 55 and 74 which are secured on shafts 63 and 64, respectively.

When the overloading of the motor is excessive or unusual, the gear 65 is rotated a greater distance which, as above described, 60 causes shafts 63 and 64 to rock the arms 73 and 74, respectively, in the direction for tightening band 60 on the drum 47, whereby further rotation of the drill is prevented.

It will be seen therefore that an ordinary 65 overloading of the drill will release the band

59 only, but should the drill meet with an unusual obstacle, such as to become engaged in a fissure in the rock, such overloading will cause the emergency band 60 to immediately lock drum 47 against rotation.

A third brake band 75 is provided on the disk clutch 30 and is provided with a manually operable lever 76 for preventing the rotation of the shaft 27, when desired, as, for instance, when removing the sections of the 75 drill rod or for connecting the same, or for any other purpose.

As shown in Fig. 2, a pinion 77 is mounted on shaft 12 within the drum 47. The pinion 77 is of such a diameter that when the drum 47 is moved to the right, as viewed in Fig. 2, by means of the clutch lever 50, the pinion will mesh with the internal gear 46, in which relation the pinion 45 will be driven directly and at the rate of rotation 80 of the shaft 12. This feature is of importance, for instance, when it is desired to lift the drill from the well, or for lowering it.

To disconnect the shaft 52 from the shaft 12, a lever 78 is provided for sliding the clutch member 51 out of engagement with the clutch member 49. The clutch will be thrown out when the apparatus is used for operating a pump or for hoisting or lowering the drill, for instance.

When the apparatus is to be used for pumping, the table gear 55 will be removed. As shown in Fig. 10, which illustrates the apparatus arranged for pumping, one end of the chain 57 is attached to the upper end of the pump rod 79. A spring 80 is positioned between the collar 81 and a stop member 82, which may be held in position by means of rods 83, or the like. The opposite end of the chain which passes over the joist 105 pulley 23 carries a counterweight 84. A spring 85 is arranged to be compressed by the weight when the pump rod 79 is in its uppermost position. The hoist pulley 23 comprises stationary shaft 86, which passes through a stationary supporting member 87 which is formed to support a number of planetary gears 88, as shown in Fig. 10. The gears 88 mesh with the teeth 89 on the hub of the gear 24 and also mesh with the 110 internal ring gear 90 of the rotatable housing member 91. When the gear 24 is driven by the pinion 25 the motion thereof is transmitted through the pinion 89 to the member 91, over which the chain 57 passes. The 115 member 91 is provided with the roller teeth 92 suitably journaled in member 91, which rollers provide suitable engagement for the links of which the chain is formed. The gears 88 and member 91 are preferably provided with roller bearings 88^a and 91^a, respectively.

The roller teeth 92 are journaled on hollow shafts 92^a the inner ends of which are open to oil (not shown) in a reservoir 91^b formed 120

by the enlarged end of the rotatable housing member 91. The roller teeth 92 are lubricated through oil openings 92^b in the shafts 92^a, the outer ends of which are closed. A disk seal 91^c prevents escape of oil from the reservoir. As will be seen in Fig. 12, the pitch of the individual links 57^a of which chain 57 is composed, is slightly greater than the pitch of the roller teeth 92. As the teeth 10 rotate to lift the chain in a counter-clockwise direction, as viewed in Fig. 12, the initial engagement of the teeth and links of the chain is at points slightly above the lowermost portion of the latter. The further rotation of the pulley brings the teeth and links into such position that the latter slide into full engagement with the teeth, the effect of which is to advance the preceding links slightly with reference to their respective 20 teeth and free them from the same, whereby the lower run of the chain drops freely from the teeth without binding or causing any dragging action.

When the apparatus is used for the pumping of oil, it is necessary that the pump rod be given a reciprocating movement and for accomplishing this object, the motor employed is of the reversible type. As shown in Fig. 14, a switch 93 is suitably pivoted, at 25 94, and has its lower end 95 suitably insulated from the remainder of the switch to provide a bridge for the contacts 96, 97 and 98. Lugs 99, 100 and 101 are provided on the motor casing as shown in Fig. 14. When the bridge member 95 of the switch lies across the contacts 96 and 97, the motor will be driven in one direction, while when the contacts 96 and 30 98 have been bridged the motor will operate in the reverse direction.

If we assume that the bridge 95 closes the circuit through contacts 96 and 98, the motor casing under sufficient load will rotate in a clock-wise direction, whereby the lug 99 will be engaged by the hook or arm 102 and move 35 the switch member to the upright or "off" position. Inasmuch as the current to the motor is cut off in this position of the switch, the spring 18 will move the motor casing to the normal central position thereof. As 40 the casing approaches center position, the intermediate lug 100 will engage the upper extension 93^a of the switch 93 and move it to the position where the bridge 95 will close the circuit through contacts 96 and 97. The 45 motor will thereupon begin to operate in the opposite direction to either lift or lower the pump shaft, as will be clear. As the load upon the motor causes the casing 15 to oscillate, the switch will automatically again be 50 set to off-position by arm 103 (as shown in Fig. 14) and the spring 18 will again bring the motor casing to the central position, whereupon the switch will be operated by lug 100 to bridge contacts 96 and 97, as above 55 described.

The springs 80 and 84, previously referred to, are compressed just prior to the termination of the down and delivery strokes of the pump, respectively. The compressing of the said springs serves to overload the motor to the extent necessary for causing the motor casing to move the switch to neutral or off position and to mechanically start the rotor in the opposite direction as the spring 18 moves the motor casing for actuating the switch from neutral to one or the other closed positions. The mechanical reversal of the motor just prior to the closing of the motor circuit, prevents damage to the motor windings as will be obvious. In Fig. 10, the pump has just completed the delivery stroke and the descending counterweight 84 has compressed the spring 85. The switch 93 will be in neutral position and as the spring 85 exerts pressure against the weight 84, the weight of the pump rod, etc. will mechanically reverse the motor, or the load will be substantially balanced as the spring 18, as above described, causes the casing 15 to snap the switch 93 to one of the "on" positions, whereupon the pump rod will descend. It will be understood that the apparatus provides for a long stroke, for instance, the stroke may be about eighty feet if the tower is one hundred feet high. As the pump rod approaches the lowermost position, the spring 80 will be compressed, the motor overloaded and the switch moved to neutral position. The spring 18 will then move the casing toward the center position whereby the switch will be moved to the other closing position, at which time the spring 80 and counterweight 84 will have mechanically reversed the motor. The arrangement is such that on the up-stroke, the motor lifts only one-half the weight of the column of oil, while the counterweight 84 lifts the other half. The apparatus is therefore economical of power consumption and operates smoothly.

The spring 85 may be provided with an enclosing support 85^a, while rails 84^a, or the like, are arranged for guiding the counterweight 84 in its up and down movement.

Although the above described improvements may be utilized for drilling and subsequently used in the same setting for pumping, a smaller unit may be used for the pumping operation, if desired, and a motor of the described type may be positioned on the top of the derrick or tower for driving the hoist pulley, the principle of the invention with reference to the pumping features remaining the same.

I have shown the motor casing 15 as provided with an exterior ring gear 104, in mesh with the pinion 105 which can be operated by a hand-wheel 106 journaled in bracket 107 mounted on the base members 10. By means of this arrangement, the motor casing can be oscillated manually for controlling or op-

erating the brake bands 59 and 60, or the switch 93.

It will be understood, of course, that my invention is applicable to drilling and pumping generally, and is not limited to oil-well operations, and I do not wish to be restricted to the apparatus above described, except where limitations thereto appear in the appended claims.

10 What I claim as new is:

1. Well drilling apparatus comprising a drill, a motor for operating said drill and having a casing oscillatable through a limited arc, and means controlled by the movement of said casing for advancing or retracting the drill.

2. Well drilling apparatus comprising a rotatable drill, and an electric motor for driving the same, and feeding means for said drill, said motor having its field arranged to move in response to the load on the motor for controlling said feeding means.

3. Well drilling apparatus comprising a drill, driving means therefor comprising a motor having a casing, means for elevating said drill from working position, and means responsive to the predetermined load of said drill for automatically actuating said elevating means for raising said drill to prevent 30 overloading, said means comprising said motor casing.

4. Well drilling apparatus comprising a drill, driving means therefor comprising a motor having a relatively movable casing, 35 means for regulating the elevation of said drill during the operation thereof, and means comprising said casing responsive to the load of said drill for automatically actuating said regulating means for causing said drill to operate at predetermined maximum capacity.

5. Well drilling apparatus comprising a drill shaft, a motor having a relatively movable casing, driving means from said motor to said shaft, and means for raising and lowering said shaft, said means comprising automatically operated power take-off mechanism associated with said driving means and being controlled by the movement of said casing.

6. Well drilling apparatus comprising a 50 drill shaft, a motor having a relatively movable casing, driving means from said motor to said shaft, means for raising and lowering said shaft, power take-off mechanism associated with said driving means, and means 55 responsive to the load on said motor for interrupting said driving means and automatically actuating said power take-off mechanism for operating said means for raising and lowering said shaft, said responsive 60 means comprising said motor casing.

7. Well drilling apparatus comprising a 65 drill, a motor, a shaft driven thereby, a second shaft for driving said drill, automatic means for making and breaking a driving connection between said shafts, a third shaft

for raising said drill, and automatic means responsive to the load on said motor for driving said third shaft from said first shaft.

8. The combination with a motor having a casing adapted to move in response to the load on said motor, of a drill, drill elevating means, and mechanism controlled by the movement of said casing for effecting a driving connection of said motor with said drill and said drill elevating means.

9. The combination with a motor having a relatively movable casing, of a drill, a drill elevating means, clutches for establishing driving connections between said motor and said drill and elevating means, and means comprising said casing responsive to the load of said motor for controlling the operation of said clutches.

10. Well drilling apparatus comprising a motor, a casing adapted for movement by the counterforce exerted by the motor under the influence of the load thereon, drilling apparatus actuated by said motor, and means actuated by the movements of said casing for controlling the actuation of said drilling apparatus.

11. Well drilling equipment comprising a drill and a shaft, a motor having a shaft, a set of gears on said motor shaft, drill elevating means, and means responsive to the load on said motor for effecting a driving engagement between said gears on said motor shaft and said drill shaft or between said gears and said drill elevating means, said responsive means comprising the casing of said motor.

12. Apparatus of the class described comprising a motor having a shaft, a drum mounted for rotation on said shaft for driving a suitable drill, said drum being provided with an internal gear, a second drum on said shaft provided with a plurality of gears meshing with said internal gear, a driving pinion on said shaft for actuating said gears, means holding said second drum stationary under normal conditions of operation, and motor actuated means for releasing said holding means under abnormal conditions whereby the driving of said drill is interrupted.

13. Apparatus of the class described comprising a motor, a shaft driven thereby, a drill shaft, transmission mechanism for transmitting power from said motor driven shaft to said drill shaft, a clutch associated with said transmission, said clutch being open during normal drilling operations, means adapted to be driven by said clutch when closed for raising said drill shaft, and means responsive to the load on said motor for automatically operating said transmission mechanism to interrupt the driving of said drill and for closing said clutch to raise said drill shaft to prevent overloading of the apparatus.

14. Apparatus of the class described comprising a motor having a shaft, drill operat-

- ing mechanism adapted to be driven thereby, drill lifting mechanism adapted to be operatively connected automatically to said shaft for actuation thereby, said lifting mechanism comprising a chain, a tower, a hoist pulley on said tower over which said chain passes, one end of said chain being attached to the drill rod, and a counterweight on the opposite end of said chain.
10. Apparatus of the class described comprising a motor having a shaft, a drill, power transmission mechanism for driving said drill, said mechanism comprising a pair of drums, brake bands therefor, one of said bands holding one of said drums stationary and the other permitting rotation of the other drum during normal drilling operations, drill elevating mechanism associated with said normally stationary drum, and means for automatically reversing the normal position of said bands upon the overloading of the motor whereby the driving of said drill is interrupted and the actuation of said drill elevating mechanism is effected through the said associated drum.
15. Apparatus of the class described comprising a motor having a shaft, a drill, power transmission mechanism for driving said drill, said mechanism comprising a pair of drums, brake bands therefor, one of said bands holding one of said drums stationary and the other permitting rotation of the other drum during normal drilling operations, drill elevating mechanism associated with said normally stationary drum, means for automatically reversing the normal position of said bands upon the overloading of the motor whereby the driving of said drill is interrupted and the actuation of said drill elevating mechanism is effected through the said associated drums, said means comprising a movable motor casing, gears actuatable thereby, a shaft driven by said gears, and arms on said shaft for operating said brake bands.
20. Well drilling apparatus comprising a motor having an oscillatable portion responsive to the load of the drill, drill feeding means associated therewith, means controlled by said portion for regulating said feeding means, and means resisting such movements of said portion and tending to urge the same to normal position.
25. Apparatus of the class described, comprising in combination a drill, a motor, driving connections between said motor and drill, drill elevating means, means for automatically interrupting the driving of said drill and for actuating said elevating means at predetermined drill load, said interrupting means comprising a planetary gear supporting drum, and an automatically controlled brake band for controlling the actuation of said drum.
30. Apparatus of the class described, comprising in combination a drill, a motor, a shaft driven thereby, driving means between said shaft and drill, said means comprising a gear, a pinion on said shaft, a set of planetary gears driven by said pinion and meshing with said gear, a rotatable member carrying said gears, means for holding said rotatable member stationary during the normal operation of said drill, drill elevating mechanism having a driving connection with said gear carrying member, and load responsive means adapted to release said holding means at predetermined load values to permit the actuation of said carrying member and elevating mechanism by said pinion.
35. In combination, a motor, a shaft driven thereby, a pair of drums on said shaft rotatable relatively thereto, a drill adapted to be driven from one of said drums, a drill elevating mechanism adapted to be actuated from said other drum, and a power take off mechanism within said drums for transmitting power from said shaft to either of said drums.
40. In combination, a motor, a shaft driven thereby, a pair of drums on said shaft rotatable relatively thereto, a drill adapted to be driven from one of said drums, a drill elevating mechanism adapted to be actuated from said other drum, and a power take-off mechanism for transmitting power from said shaft to either of said drums, each of said drums being provided with an automatically controlled brake band.
45. In combination, a motor, a shaft driven thereby, a pair of drums on said shaft rotatable relatively thereto, a drill adapted to be driven from one of said drums, a drill elevating mechanism adapted to be actuated from said other drum, load responsive means, and a power take-off mechanism for transmitting power from said shaft to either of said drums, said take-off mechanism being controlled by said load responsive means.
50. In combination, a motor, a shaft driven thereby, a pair of drums on said shaft rotatable relatively thereto, a ring gear on the first of said drums, a set of planetary gears on the second drum in mesh with said ring gear, a second gear rotatable with said shaft and adapted to drive said planetary gears, a brake band on said second drum, a drill driven from said first drum, drill elevating mechanism actuatable by said second drum, and load responsive means for releasing said brake band, whereby said second drum is free to rotate and to actuate said drill elevating mechanism.
55. In combination, a motor, a shaft driven thereby, a drill, drill elevating apparatus, power take-off mechanism for driving said drill and elevating apparatus from said shaft, load responsive means for controlling said power take-off mechanism, said elevating apparatus comprising a clutch, and means actuatable by said responsive means for releas-

ing said clutch at a predetermined reduction of said load whereby said drill is movable into full load drilling position.

25. In combination, a motor, a shaft driven thereby, a drum on said shaft rotatable relatively thereto, a drill adapted to be driven from said drum, a normally stationary second drum on said shaft carrying a set of planetary gears, a pinion rotatable with said shaft for driving said gears, a ring gear on said first drum meshing with said gears for actuating said first drum during normal drilling operations, drill elevating mechanism adapted to be driven by said second drum, said mechanism comprising a clutch, a brake for said second drum, and load responsive means for releasing said brake upon predetermined over-load, whereby said second drum and elevating means are actuated.

26. In combination, a motor, a shaft driven thereby, a drum on said shaft rotatable relatively thereto, a drill adapted to be driven from said drum, a normally stationary second drum on said shaft carrying a set of planetary gears, a pinion rotatable with said shaft for driving said gears, a ring gear on said first drum meshing with said gears for actuating said first drum during normal drilling operations, drill elevating mechanism adapted to be driven by said second drum, said mechanism comprising a clutch, a brake for said second drum, and load responsive means for releasing said brake upon predetermined over-load, whereby said second drum and elevating means are actuated, said responsive means automatically setting said brake and releasing said clutch whereby the resumption of normal drilling operations is effected upon reduction of said load.

27. In combination, a motor, a shaft driven thereby, a sun-gear on said shaft, a drum rotatable relatively to said shaft and being provided with a set of planetary gears driven by said sun-gear, a pinion rotatable with said drum, drill elevating mechanism driven by said pinion, a second relatively rotatable drum on said shaft provided with a ring-gear meshing said planetary gears whereby said second drum is driven during normal drilling operations, a drill operatively connected to said second drum, a brake having bands for each of said drums, the brake for said first drum being in set position to hold said drum stationary, and the brake of said second drum being released during normal drilling operations, and load responsive means operatively associated with said bands for reversing the relations of said brakes upon predetermined overload, whereby said drilling operation is stopped and the drill elevated to release the overload thereon.

28. In combination, a motor, a shaft driven thereby, a relatively rotatable drum thereon, a reduction gearing for driving said drum from said shaft, a drill actuatable from said

shaft, drill hoisting and lowering mechanism actuatable by said drum, and means for eliminating the reducing action of said gearing for driving said drum at the speed of said shaft for increasing the speed of the hoisting or lowering mechanism.

29. In combination, a motor, a shaft driven thereby, a drum relatively rotatable thereon, reduction gearing for driving said drum from said shaft, a drill actuatable from said shaft, drill hoisting and lowering mechanism actuatable by said drum, and means for locking said whereby said drum is driven at the speed of said shaft.

30. In combination, a motor, a shaft driven thereby, a drum relatively rotatable thereon, reduction gearing for driving said drum from said shaft, a drill actuatable from said shaft, drill hoisting and lowering mechanism actuatable by said drum, means for locking said gearing whereby said drum is driven at the speed of said shaft, said means comprising a gear, and means for causing the same to mesh with one of said other gears.

31. In combination, a motor, a shaft driven thereby, a drum relatively rotatable thereon, reduction gearing for driving said drum from said shaft, a drill actuatable from said shaft, drill hoisting and lowering mechanism actuatable by said drum, means for locking said gearing whereby said drum is driven at the speed of said shaft; said means comprising a gear, and means for causing the same to mesh with one of said other gears, said last named means comprising a gear carrying member slidably axially of said shaft.

32. In combination, a motor, a shaft driven thereby, a relatively rotatable drum on said shaft, a drill adapted to be driven from said drum, a ring gear carried by said drum, a second relatively rotatable drum on said shaft carrying a set of planetary gears in mesh with said ring gear, a sun-gear rotatable with said shaft for driving said planetary gears, and means for holding said second drum stationary whereby power is transmitted from said shaft by said gears to said drum for driving said drill.

33. In combination, a motor, a shaft driven thereby, a relatively rotatable drum on said shaft, a drill adapted to be driven from said drum, a ring gear carried by said drum, a second relatively rotatable drum on said shaft carrying a set of planetary gears in mesh with said ring gear, a sun-gear rotatable with said shaft for driving said planetary gears, and means for holding said second drum stationary whereby power is transmitted from said shaft by said gears to said drum for driving said drill, said holding means comprising a brake band on said drum.

34. In combination, a motor, a shaft driven thereby, a relatively rotatable drum on said shaft, a drill adapted to be driven from said drum, a ring gear carried by said drum, a

second relatively rotatable drum on said shaft carrying a set of planetary gears in mesh with said ring gear, a sun-gear rotatable with said shaft for driving said planetary gears, means for holding said second drum stationary whereby power is transmitted from said shaft by said gears to said drum for driving said drill, said holding means comprising a brake band on said drum, and load responsive means adapted to release said brake band upon predetermined overload for interrupting the drilling operation.

35. Apparatus of the class described comprising a motor, a shaft driven thereby, a drill, means for transmitting power from said shaft to said drill, drill elevating mechanism, means for transmitting power from said shaft to said mechanism, said means comprising a clutch, and load responsive means for controlling the actuation of said last named means, said load responsive means being operatively associated with said clutch whereby the latter is released upon removal of said overload to thereby automatically maintain said drill in position for substantially maximum drilling operation.

36. In combination, a motor, a shaft driven thereby, a pair of relatively rotatable drums on said shaft, a drill actuatable by one of said drums, drill elevating mechanism actuatable by the second of said drums, planetary gear mechanism associated with said drums for driving the latter from said shaft, and load responsive means for controlling the driving of said drum by said shaft, said means being adapted to permit the actuation of said elevating mechanism to reduce overloads on said drill.

37. In combination a motor, a shaft driven thereby, a pair of relatively rotatable drums on said shaft, a drill actuatable by one of said drums, drill elevating mechanism actuatable by said second of said drums, planetary gear mechanism associated with said drums for driving the latter from said shaft, and load responsive means for controlling the driving of said drum by said shaft, said means being adapted to permit the actuation of said elevating mechanism to reduce overloads on said drill, said responsive means serving also to interrupt said first drum upon sudden overload.

38. In combination, a motor, a shaft driven thereby, a drill, a drum for effecting a driving connection between said shaft and drill, drill elevating mechanism comprising a clutch, a second drum for effecting a driving connection between said shaft and mechanism, a brake band on said first drum permitting rotation thereof during normal drilling operations, a band on said second drum holding the same stationary during normal drilling operations, and load responsive means operatively associated with said band and clutch whereby said second drum

and clutch serve to maintain said drill under predetermined maximum load conditions, said first band being operable by said responsive means to stop rotation of the drill on sudden excess overload.

39. In combination, a motor, a drill driven thereby, drill feeding and elevating mechanism comprising a clutch, load responsive means for controlling the operation of said mechanism, and a clutch operating means actuatable by said responsive means to release said clutch for automatically feeding said drill toward the work.

40. In combination, a motor, a drill driven thereby, drill feeding and elevating mechanism comprising a clutch, load responsive means for controlling the operation of said mechanism, and a clutch operating means actuatable by said responsive means to release said clutch for automatically feeding said drill toward the work, said clutch operating means comprising a member having a threaded connection with said clutch and being movable in said threads by said responsive means.

41. In combination, a motor, a drill operable thereby, a drill elevating and feeding mechanism comprising a clutch having a depending threaded sleeve, load responsive means comprising a reciprocable member, a gear actuatable thereby, and a clutch operating member having teeth meshing with said gear and being adapted to coact with said threaded sleeve in releasing and closing said clutch.

42. In combination, a motor, a drill driven thereby, a drill elevating and feeding mechanism comprising a clutch, a drum actuatable by said motor for driving said mechanism through said clutch, a brake band on said clutch, and load responsive means associated with said band and clutch, whereby said clutch is released for feeding said drill and said band is released to permit said drum to actuate said mechanism to prevent overloading.

43. In combination, a motor, a drill, means for driving the latter from the former comprising a drum, a brake band therefor, drill elevating and feeding mechanism comprising a clutch, a second drum driven by said motor adapted to actuate said mechanism, a band for said second drum, and load responsive means operatively connected with said bands and clutch for automatically controlling the actuation of said drill and the feeding of the same to the work.

44. In combination, a motor, a drill, means for driving the latter from the former comprising a drum, a brake band therefor, drill elevating and feeding mechanism comprising a clutch, a second drum driven by said motor adapted to actuate said mechanism, a band for said second drum, load responsive means operatively connected with said bands and clutch for automatically controlling the

actuation of said drill and the feeding of the same to the work, said connections comprising a gear actuatable by said responsive means, levers movable thereby for controlling said bands, and a clutch operating member having a toothed sector in mesh with said gear.

45. In combination, a motor, a rotatable drill, means for driving the latter from the former comprising a drum, a brake band therefor, drill elevating mechanism, a second drum actuatable by said motor for driving said mechanism, a brake band for said second drum, a load responsive member, and means for actuating said bands from said member, said means comprising a gear driven by said member, a toothed member meshing with said gear and operatively connected to said bands.

46. In combination, a motor, a rotatable drill, means for driving the latter from the former comprising a drum, a brake band therefor, drill elevating mechanism, a second drum actuatable by said motor for driving said mechanism, a brake band for said second drum, a load responsive member, and means for actuating said bands from said member, said means comprising a gear driven by said member, a toothed member meshing with said gear and operatively connected to said bands, said toothed member being adjustable for varying the load range of said drill.

47. Apparatus of the class described comprising a motor, a drill, means for driving the latter from the former comprising a drum, a brake band therefor, drill elevating mechanism, a second drum actuatable by said motor, a band for said second drum, a pair of shafts connected to said bands for operating the same, said shafts being operatively connected whereby rotation of one effects the rotation of the other, a lever attached to one of said shafts, a load responsive member, a gear actuatable thereby, and a member actuatable by said gear and engageable with said lever for actuating the same upon predetermined maximum and minimum loads whereby said shafts are rotated and said bands operated to control the elevating and drilling operations.

48. Apparatus of the class described, comprising a motor, a rotatable drill, means for driving the latter from the former comprising a drum provided with a brake band, a drill elevating and feeding mechanism comprising a tower having winding means thereon, a flexible member supporting said drill from said winding means, a second drum provided with a brake band and adapted to be actuated by said motor, power transmitting means from said second drum to said winding means, said transmitting means comprising a clutch, a load responsive member operatively associated with said bands and clutch

whereby said first drum is rotated during normal drill loads and said second drum is rotated upon overloading to operate said winding means to elevate said drill, said clutch being opened upon predetermined underloading to permit said drill to gravitate toward the work.

In testimony whereof, I have subscribed my name.

JOHN BRICKEN.

CERTIFICATE OF CORRECTION.

Patent No. 1,776,779.

Granted September 30, 1930, to

JOHN BRICKEN.

It is hereby certified that error appears in the printed specification of the above numbered patent requiring correction as follows: Page 7, line 48, claim 27, after the word "meshing" insert the word with, and in line 78, claim 29, after "said" first occurrence, insert the word gearing; and that the said Letters Patent should be read with these corrections therein that the same may conform to the record of the case in the Patent Office.

Signed and sealed this 25th day of November, A. D. 1930.

(Seal)

M. J. Moore,
Acting Commissioner of Patents.
